Des. 218,784
Patented Sept. 22, 1970

218,784

PRESS FOR BONDING PLASTIC MATERIAL OR THE LIKE

Theodore R. Finke, Euclid, Ohio, assignor to The Euclid
Products Co., Inc., Willoughby, Ohio, a corporation of
Ohio

Filed Mar. 28, 1969, Ser. No. 16,501

Term of patent 14 years

Int. Cl. D15—05

U.S. Cl. D63—1

Fig. 1

Fig. 2

FIG. 1 is a perspective view showing the front, top and one side of a press for bonding plastics or the like embodying my new design; and

FIG. 2 is another perspective view showing the rear, top and other side thereof.

I claim:

The ornamental design for a press for bonding plastic material or the like, substantially as shown and described.
